UNITED STATES PATENT OFFICE

2,232,506

HYDRAULIC POWER LIFT

Russel D. Acton, Chicago, Ill., assignor to International Harvester Company, a corporation of New Jersey

Application January 19, 1939, Serial No. 251,785

16 Claims. (Cl. 97—50)

The present invention relates generally to power operated lifting devices for tractors. More specifically the invention relates to a hydraulic type of power lift mechanism.

5 The principal object of the invention is to provide a power lift device having two lifting elements which are operated consecutively to lift successively two implements, or to perform any two similar functions in a timed sequence relation.

Another object is to provide a hydraulic power lift mechanism which can be operated to lift first implements at the front of the tractor and to subsequently lift implements at the rear of the 15 tractor, the operation being automatic and achieved without additional actuation of valve means by an operator.

Another object, which is in a sense a completion of the above object, is to provide a power lift mechanism which reverses the lifting operation and lowers the front implement before lowering the rear implement.

The above objects and others, which will be apparent from the detailed description to follow, 20 are accomplished by mounting a hydraulic lift mechanism utilizing a vane-type piston, such as disclosed and claimed in the Johnston Patent No. 2,039,801, May 5, 1936. By utilizing vane-type pistons in two way cylinders generally semicylindrical in shape, the movement of the vane in one of the cylinders may be utilized to open communication with the other cylinder, whereby one of the vanes is operated subsequently to the other. By providing a suitable valve arrangement and 25 the proper communicating conduits, the action may be reversed to return the vanes to their original position in the same order. Suitable control valve means and properly located conduits are provided for delivering the liquid under pressure from the pump to the proper side of the vane and for allowing the escape of liquid from the other side of the vane to the reservoir or low pressure side of the pump. In order to provide a mechanism in which the supply of high pressure 30 liquid is rendered ineffective after the vane has completed its stroke, valve means are utilized which are automatically operated by movement of the last vane to be operated into its final position at the end of the stroke.

In the drawings:

Figure 1 is a side elevation of a tractor with one of the drive wheels removed, showing a power lift housing incorporating the invention and the 35 side of the tractor at which there is a lifting con-

nection with an implement at the front of the tractor;

Figure 2 is a view of the other side of the same tractor and lifting arrangement, showing the side of the tractor at which there is a connection to an implement at the rear of the tractor;

Figure 3 is a rear view of the power lift housing in its position on the frame of the tractor with certain portions broken away in section to show the vane chamber construction and the construction of the controlling valve;

Figures 4 and 5 are sections taken on the line A—A of Figure 3, showing the control valve in its two positions for lifting or for lowering;

Figure 6 is a section taken on the line B—B 15 of Figure 3 and Figure 11 with the vane in one position;

Figure 7 is a section taken on the line B—B of Figure 3 and Figure 11 with the vane at the end of its stroke in its other position;

Figure 8 is a section taken on the line 8—8 of Figure 3 and Figure 11;

Figures 9 and 10 are sections taken on the lines C—C of Figure 3 and Figure 11;

Figure 11 is a horizontal section taken substantially on the line 11—11 of Figure 6, certain portions of the valve housing and of the shaft supporting portions of the power lift housing being shown in top plan view to better illustrate the construction thereof; and,

Figure 12 is a horizontal section taken along the line 12—12 of Figure 10.

The tractor illustrated includes a frame 10 having laterally extending axle housings 11, on which rear drive wheels 12 are mounted. In Figure 2, front wheels 13 are shown as well as other units of the tractor at the forward end thereof, which will not be described in detail.

At the rear of the tractor, downwardly depending brackets 14 provide means for connecting implement beams 15 extending rearwardly and carrying soil-working tools 16. Lifting links 17 connected to the beams at their lower ends are connected at their upper ends to lifting arms 18 carried by a transverse shaft 19. Said shaft is 45 carried on a pair of supporting members 20 connected to the rear axle structures and extending rearwardly therefrom.

At the front end of the tractor, implement beams 21, on which soil-working tools 22 are 50 mounted, are pivotally supported on a shaft 23 carried by brackets 24 connected to the tractor. Lifting levers 25, connected to the beams at their upper ends, are connected at their upper ends to push bars 26. Said bars are mounted on the

levers 25 to raise the rear ends of the beams 21 on forward movement thereof and to thereby lift the front implements. The bars 26 are connected to arms 27 on a lifting rockshaft 28 mounted on brackets 29 at an intermediate point on the tractor adjacent the rear end thereof.

The power lift housing, which will be designated in its entirety by the numeral 30, is mounted on a base 31, which is in turn mounted 10 on the rear of the frame structure 10 of the tractor. Said power lift housing is made up of a section 32 provided with a flange 33 for mounting above the base 31 and a section 34 provided with a flange.

15 The section 32 is provided with a sleeve-like hub extension 36 in which a lifting shaft 37 is journaled. At its outer end said shaft is provided with a crank 38, which is connected by a lifting link 39 with one of the arms 27 carried by the rockshaft 28.

20 The housing section 34 is formed with a sleeve-like hub extension 41, in which a lifting shaft 42 is journaled. Said shaft is provided with a lifting crank 43 connected by a link 44 with a 25 lifting lever 45 on the rockshaft 19.

25 The housing section 32 is formed with a chamber 46 generally semicylindrical in shape, being, however, substantially more in angular extent than 180 degrees. Said chamber is open at the 30 inner face of the housing section to provide for the insertion of the vane 47. Said vane is mounted in a slot formed in an enlarged hub 48 formed integrally on the end of the lifting shaft 37. The vane 47 is adapted to oscillate in the chamber 46, forming a substantial liquid seal therewith. Leakage of a certain amount of liquid is not a significant feature in a device of this type where an excess amount of fluid is being supplied by a pump having sufficient capacity to take care 40 of any small leaks. The chamber 46 forms in effect a cylinder, and the vane 47 forms a piston oscillating therein. Insofar as the invention is concerned, the terms cylinder and piston will be used with the intention of including any other 45 type of hydraulic device utilizing an expandable chamber and a piston operating therein.

50 The housing section 34 is formed with a chamber 49 identical in shape and size with the chamber 46. A vane 50 is mounted in the chamber 55 in a hub 51 carried on the lifting shaft 42. This construction is a duplication of the construction at the other side of the housing.

To complete the housing 30, the housing sections 32 and 34 are brought together with their 55 open ends abutting a partition or dividing member in the form of a plate 52. The entire construction is held as a unit by long cap-screws 53 extending through the housing section 32 and the plate 52 into the housing section 34.

60 Referring to Figure 6, it will be noted that the hub 48 of the lifting shaft 37 fits against a cylindrical surface formed by a projecting portion 54 at the bottom of the housing section to form a seal against passage of liquid from one side of 65 the crescent-shaped chamber or compartment 46 to the other side. The same provision is made in the housing section 34 by a projecting portion 55 of the bottom wall of the housing section.

70 A hydraulic pump 56 is illustrated as being mounted at the rear of the frame structure 10 of the tractor. Said pump contains any suitable pump mechanism adapted to be operated from power derived from the tractor engine. A construction such as disclosed in the Johnston patent 75 above referred to may be utilized as one example

of a means for supplying liquid under pressure.

A discharge conduit 57 leading from the pump 56 is connected with a conduit 58 formed in a valve body portion 59 of the housing section 34. Said conduit extends vertically upwardly, terminating in a flat face 60. A valve 61, circular in cross-section, is mounted on the face 60, being held rotatably thereagainst by a coupling member 62 threaded on a cylindrical upper portion of the body 59. The valve 61 is provided with an operating handle 63 adapted to be engaged by an operator on the tractor for lifting and lowering the implements by means of the power lift mechanism.

15 As shown in Figure 4, the valve 61 is in position to transfer liquid under pressure delivered through the conduit 58 through a channel 64 formed in the valve to a conduit 65 extending vertically downwardly through the valve body portion 59 and laterally therefrom through a passage 66 in the plate 52 into a conduit 67 formed in the housing section 32. The conduit 67, as shown in Figure 11, terminates in the compartment, or cylinder as it has been referred to, 46 beneath the vane 47 when in the position shown 25 in Figure 6.

30 The operation of the power lift constituting this invention will be described along with the description of the elements and their relative arrangement. Fluid under pressure supplied beneath the vane 47 rotates said vane, the hub 48, and the lifting shaft 37 into the position in Figure 7. During this movement, the lifting crank 38 is moved from the position, as shown in Figure 1, to the dotted line position. It will be noted 35 that both positions are past dead-center with respect to a center line between the axis of the lifting shaft 37 and the point of connection of the link 39 with the lever 40. This type of lifting arrangement is self-locking when it has reached 40 its final position. This feature is disclosed and claimed in the Johnston patent previously referred to. It is a particularly important feature, however, in connection with the present invention, as, when one vane has completed its lifting 45 function, it is automatically locked in position without maintaining liquid pressure or without other locking means. This makes possible operating the second vane without giving any further consideration to the liquid pressures at opposite 50 sides of the vane first operated.

55 As the vane 47 moves from the position shown in Figure 6 to the position shown in Figure 7, liquid on the low pressure side of the vane is forced out through a conduit 68 formed in the housing section 32. This conduit is shown in dotted lines in Figure 6 and in full lines in Figure 11. The conduit 68 is connected by a passage 69 in the plate 52 with a conduit 70 formed in the section 34. Said conduit has a vertical extension 60 terminating in the face 60, as shown in Figure 11. With the valve in the position shown in Figure 4, liquid escaping at low pressure through the conduits 68 and 70 is transferred by a channel 71 to a return conduit 72. Said conduit has 65 a vertical portion terminating in the face 60 and a horizontal portion, shown in Figures 10 and 11, extending into a supply reservoir 73 formed in the housing section 34. To return liquid from the reservoir 70 to the pump 56, a conduit 74 is connected with the reservoir at one end with the inlet side of the pump at its other end.

70 The description above completes the first cycle in the lifting operation. The description will proceed with details of the valve mechanism and 75

the conduits which operate the second vane after the first vane has completed its lifting operation.

When the vane 47 reaches the position shown in Figure 7, a conduit 78, formed in the hub 48, comes into communication with a conduit 76 formed in the plate 52, as shown in Figure 11. The conduit 76 is also shown in the view of the plate 52 in Figure 8. Fluid under pressure is then supplied to the underneath side of the vane 50 in the second compartment 49 formed in the housing section 34. The vane 50 with the hub 51 and the shaft 42 is then rotated into the position shown in Figure 10.

During movement of the vane 50, liquid on the low pressure side of the vane escapes through a conduit 77 formed in the housing section 34. Said conduit extends horizontally to the valve portion of the housing section and then vertically terminating in the valve face 60. The channel 71 in the valve 62 previously referred to is extended to cover the outlet of the conduit 77. Fluid escaping through said conduit is transferred by the channel 71 to the conduit 72. As previously described, said conduit delivers the liquid under low pressure into the reservoir 73.

When the vane 50 has completed its cycle of movement in the angular direction being described, the crank 43, carried by the shaft 42, has moved into position shown in Figure 2, thereby lifting the implements at the front of the tractor. Said crank passes into a dead-center position due to angular movement of substantially more than 180 degrees of the lifting shaft 42. This acts to lock the implements in lifted position, thereby not requiring any hydraulic lock of the vane in its chamber. It will be noted that the crank 43 is also in a dead-center position when the implements are in working position, as shown by the full lines in Figure 2. This construction makes possible the use of spring pressure on the implements, if desired, and prevents unlimited floating action in an upward direction.

When the vane 50 reaches its position of rest, as shown in Figure 10, a conduit 78, formed in the hub 51, comes into registration with a by-pass conduit 79 communicating with the reservoir 73, as shown in Figure 12. Pressure is thereby entirely released in the system, as there is no substantial resistance to flow, and liquid circulated by the pump passes back into the reservoir 73.

The first two steps of a complete cycle of the power lift of this invention as above described lifts the front implement and subsequently lifts the rear implement. The operator of the tractor may then turn at the end of the rows or leave the implement in lifted position for transport. When it is desired to lower the implements, the power lift device, as described, is capable of first lowering the front implements as the tractor starts from the end of the row and subsequently and automatically lowering the rear implements. This is a very desirable feature for row crop cultivation. Another advantage is that the load on the lifting mechanism is divided, so that a smaller and less powerful lifting mechanism will handle a larger load by lifting a half at each step.

When the implements are to be lowered, the valve 61 is shifted 90 degrees into the position shown in Figure 5. With the valve in this position, the channel 64 forms a communication between the high pressure inlet conduit 57 and the conduit 70 leading to the underneath side of the

vane 47. The channel 71 forms a by-pass communication to the reservoir between the conduit 67 continued as 65 and a conduit 80. As shown in Figure 11, the conduit 80 communicates with the chamber 49 and with the face 61 in a position to come into registration with the extended portion of the channel 71 when the valve is in the position shown in Figure 5. It will be noted that the conduit 80 is covered and maintained inoperative during the lifting operation. The conduit 71, which shows in dotted lines in Figure 5, is closed during the reverse or lowering operation.

As fluid under pressure is supplied through the conduit 70 and the conduit 68, the vane 47 and the elements associated therewith are rotated from the position shown in Figure 7 to the position shown in Figure 6. At the completion of the movement or stroke, a conduit 81, formed in the hub 48, comes into registration with a conduit 82 formed in the plate 52, as shown in Figures 8 and 11. The high pressure fluid is then delivered to the underneath side of the vane 50, moving it from the position shown in Figure 10 to the position shown in Figure 9.

During movement of the vane 47 to the position shown in Figure 6, fluid at the low pressure side of the vane flows out through the conduits 67 and 65 and is transferred by the channel 71 to the conduit 72 leading to the reservoir 73.

As the vane 50 is rotated to the position shown in Figure 9, fluid at the low pressure side escapes through the conduit 80, being transferred by the channel 71 to the conduit 72 leading to the reservoir.

As the vane 50 comes to rest at the end of its stroke, a conduit 83 formed in the hub 51 comes into registration with the by-pass conduit 79, allowing the liquid being delivered by the pump to return to the reservoir without appreciable resistance to flow.

It will be understood that, with the reverse motions of the vanes as above described, the lifting cranks 38 and 43 are returned to their original positions, as shown in solid lines in Figure 1 and 2.

The double lift mechanism of applicant's invention has been described as being incorporated in a hydraulic device of the vane type as applied to a tractor for lifting implements positioned at the front and rear thereof. It is to be understood, however, that applicant does not limit his claim to invention to the particular construction described. Any type of hydraulic device is considered as coming within the scope of the appended claims in which, upon actuation of a valve means by an operator, one lifting mechanism functions to complete its cycle, at the end of which or following which a second hydraulic mechanism is automatically brought into operation.

Although applicant has shown a particular valve mechanism incorporated as a part of the hydraulic piston, any type of valve mechanism or other functional equivalent can be utilized within the scope of the invention which will obtain the result of automatically and successively putting one hydraulic mechanism into operation following and as a result of the operation of a first mechanism.

What is claimed is:

1. A power lift device for tractors having two implements mounted thereon comprising a hydraulically operated lifting unit connected to each implement, means for supplying liquid under

pressure to each unit, valve means incorporated in the supply means operable for delivering liquid to one unit, and means initiated by the actuation of said unit to supply thereafter liquid under 5 pressure to the other unit.

2. A power lift device for tractors having two implements mounted thereon comprising a pump adapted to be driven by power derived from the tractor, a hydraulically operated lifting unit connected to each implement, means for supplying liquid under pressure from the pump to each unit, valve means incorporated in the supply means operable for delivering liquid to one unit, and means initiated by the actuation of said 10 unit to supply thereafter liquid under pressure to the other unit.

3. A power lift device for tractors having implements mounted independently at the front and rear thereof comprising hydraulically operated lifting means independently connected to each implement, means for supplying liquid under pressure to said lifting means, valve means for delivering liquid first to the lifting means connected to the front implement, and means operable upon actuation of said lifting means to supply liquid under pressure to the lifting means connected to the rear implement.

4. A power lift device for tractors having implements mounted independently at the front and rear thereof comprising a pump adapted to be driven by power derived from the tractor, hydraulically operated lifting means independently connected to each implement, means for supplying liquid under pressure from the pump to said 30 lifting means, valve means for delivering liquid first to the lifting means connected to the front implement, and means operable upon actuation of said lifting means to supply liquid under pressure to the lifting means connected to the rear implement.

5. A power lift device for tractors having implements mounted independently at the front and rear thereof comprising a pump adapted to be driven by power derived from the tractor, hydraulically operated lifting means independently connected to each implement, means for supplying liquid under pressure from the pump to said lifting means, valve means for delivering liquid first to the lifting means connected to the front 45 implement, and valve means incorporated in a movable element of the lifting means operable upon completion of the actuation of said lifting means to by-pass the liquid under pressure to the lifting means connected to the rear implement.

55 6. A power lift device for tractors having two implements mounted thereon comprising a pump adapted to be driven by power derived from the tractor, two hydraulically operated cylinder and piston devices, each being independently connected to one implement, means for supplying liquid under pressure from the pump to said cylinders including valve means manually operable to deliver liquid first to the cylinder of one of the devices, and means initiated by the actuation of the one of the devices to supply thereafter liquid under pressure to the other cylinder.

7. A power lift device for tractors having two implements mounted thereon comprising a pump adapted to be driven by power derived from the 70 tractor, two hydraulically operated cylinder and piston devices, each being independently connected to one implement, means for supplying liquid under pressure from the pump to said cylinders including valve means operable to deliver liquid first to the cylinder of one of the de-

vices, and means operable by completion of the stroke of the piston of said device to supply liquid under pressure to the other cylinder.

8. A power lift device for tractors having two implements mounted thereon comprising a pump 5 adapted to be driven by power derived from the tractor, two hydraulically operated cylinder and piston devices, each having independently connected to one implement, means for supplying liquid under pressure from the pump to said cylinders including valve means manually operable to deliver liquid first to the cylinder of one of the devices, and automatically operable valve means operable by completion of the stroke of the piston of said device to supply liquid under pressure to 10 the other cylinder.

9. In a tractor having two implements mounted thereon, and a liquid pump driven by power derived from the motor, and, in combination therewith, a hydraulic power lift casing mounted on the tractor, said casing being formed with two substantially semi-cylindrical chambers, a lifting shaft extending laterally from each lift chamber, said shafts being independently connected to the implements, a vane type piston 20 mounted in each chamber on the lifting shaft therein, means for conducting liquid under pressure from the pump to the cylinders and means for returning liquid at low pressure from the cylinders to the inlet of the pump, and valve means for first supplying liquid under pressure to one side of one vane to thereby lift one implement, said vane being operable at the completion of its stroke to open liquid supply means to one side of the second vane, whereby said vane 30 is operated to lift the other implement at the rear of the tractor.

10. In a tractor having a liquid pump driven by power derived from the motor, and, in combination therewith, a hydraulic power lift casing mounted on the tractor, said casing being formed with two substantially semi-cylindrical chambers, a lifting shaft extending laterally from each lift chamber, said shafts being independently connected to the implements, a vane type piston 40 mounted in each chamber on the lifting shaft therein, means for conducting liquid under pressure from the pump to the cylinders and means for returning liquid at low pressure from the cylinders to the inlet of the pump, and valve means for first supplying liquid under pressure to one side of one vane to oscillate one shaft, said vane being operable at the completion of its stroke to open liquid supply means to one side of the second vane, whereby said vane 50 is operated to oscillate the other shaft.

11. In a tractor having an implement mounted at the front thereof, and an implement mounted at the rear thereof, and a liquid pump driven by power derived from the motor, and, in combination therewith, a hydraulic power lift casing mounted at the rear of the tractor, said casing being formed with two substantially semi-cylindrical chambers, a lifting shaft extending 60 laterally from each chamber, one of said shafts being connected to the implement at the front of the tractor and the other to the implement at the rear, a vane type piston mounted in each chamber on the lifting shaft therein, means for conducting liquid under pressure from the pump to the cylinders, means for returning liquid at low pressure from the cylinders to the inlet of the pump, and valve means for first supplying liquid 65 under pressure to one side of one vane to 70

75

thereby lift the implement at the front of the tractor, said vane being operable at the completion of its stroke to open liquid supply means to one side of the second vane, whereby said vane is operated to lift the implement at the rear of the tractor.

12. In a tractor having two implements mounted thereon, and a liquid pump driven by power derived from the motor, and, in combination therewith, a hydraulic power lift casing mounted on the tractor, said casing being in two sections and being formed with semi-cylindrical chambers open at adjacent sides, a port plate between said sections, a lifting shaft extending laterally from each chamber, each of said shafts being independently connected to an implement, a vane type piston mounted in each cylinder on the lifting shaft therein, means for conducting liquid under pressure from the pump to the chambers and means for returning liquid at lower pressure from the chambers to the inlet of the pump, and valve means for first supplying liquid under pressure to one side of one vane to thereby lift one implement, said vane being operable at the completion of its stroke to open liquid supply means formed in the port plate to deliver under pressure to one side of the second vane, whereby said latter vane is operated to lift the other implement.

13. In a tractor having an implement mounted at the front thereof and an implement mounted at the rear thereof, and a liquid pump driven by power derived from the motor, and, in combination therewith, a hydraulic power lift casing mounted at the rear of the tractor, said casing being in two sections and being formed with semi-cylindrical chambers open at adjacent sides, a port plate between said sections, a lifting shaft extending laterally from each chamber, one of said shafts being connected to the implement at the front of the tractor and the other of said shafts being connected to the implements at the rear of the tractor, a vane type piston mounted in each cylinder on the lifting shaft therein, means for conducting liquid under pressure from the pump to the chambers and means for returning liquid at lower pressure from the chambers to the inlet of the pump, and valve means for first supplying liquid under pressure to one side of one vane to thereby lift the implement at the front of the tractor, said vane being operable at the completion of its stroke to open liquid supply means formed in the port plate to deliver liquid under pressure to one side of the second vane, whereby said vane is operated to lift the implement at the rear of the tractor.

14. In a tractor having a liquid pump thereon driven by power derived from the motor, and, in combination therewith, a hydraulic power lift casing mounted on the tractor, said casing being in two sections and being formed with semi-cylindrical fluid chambers open at adjacent sides, a port plate between said sections, a lifting shaft extending laterally from each chamber, one of said shafts being connected to the implement at the front of the tractor and the other of said shafts being connected to the implements at the rear of the tractor, a vane type piston mounted in each cylinder on the lifting shaft therein, means for conducting liquid under pressure from the pump to the chambers and means for returning liquid at lower pressure from the chambers to the inlet of the pump, and valve means for first supplying liquid under pressure to one side of one vane to thereby lift the implement at the front of the tractor, said vane being operable at the completion of its stroke to open liquid supply means formed in the port plate to deliver liquid under pressure to one side of the second vane, whereby said vane is operated to lift the implement at the rear of the tractor.

15. In a tractor having a liquid pump thereon driven by power derived from the motor, and, in combination therewith, a hydraulic power lift casing mounted on the tractor, said casing being in two sections and being formed with semi-cylindrical fluid chambers open at adjacent sides, a port plate between said sections, a lifting shaft extending laterally from each chamber, one of said shafts being connected to the implement at the front of the tractor and the other of said shafts being connected to the implements at the rear of the tractor, a vane type piston mounted in each cylinder on the lifting shaft therein, means for conducting liquid under pressure from the pump to the chambers and means for returning liquid at lower pressure from the chambers to the inlet of the pump, and valve means for first supplying liquid under pressure to one side of one vane, said vane being operable at the completion of its stroke to open liquid supply means formed in the port plate to deliver liquid under pressure to one side of the second vane.

16. In a tractor having a liquid pump thereon driven by power derived from the motor, and, in combination therewith, a hydraulic power lift casing mounted on the tractor, said casing being in two sections and being formed with semi-cylindrical fluid chambers open at adjacent sides, a port plate between said sections, a lifting shaft extending laterally from each chamber, one of said shafts being connected to the implement at the front of the tractor and the other of said shafts being connected to the implements at the rear of the tractor, a vane type piston mounted in each cylinder on the lifting shaft therein, means for conducting liquid under pressure from the pump to the chambers and means for returning liquid at lower pressure from the chambers to the inlet of the pump, and valve means for first supplying liquid under pressure to one side of one vane and for draining fluid at low pressure from the other side of the vane, said vane being operable at the completion of its stroke to open liquid supply means formed in the port plate to deliver liquid under pressure to one side of the second vane, said valve means providing for draining liquid at low pressure from the other side of said vane.

17. In a tractor having a liquid pump thereon driven by power derived from the motor, and, in combination therewith, a hydraulic power lift casing mounted on the tractor, said casing being in two sections and being formed with semi-cylindrical fluid chambers open at adjacent sides, a port plate between said sections, a lifting shaft extending laterally from each chamber, one of said shafts being connected to the implement at the front of the tractor and the other of said shafts being connected to the implements at the rear of the tractor, a vane type piston mounted in each cylinder on the lifting shaft therein, means for conducting liquid under pressure from the pump to the chambers and means for returning liquid at lower pressure from the chambers to the inlet of the pump, and valve means for first supplying liquid under pressure to one side of one vane and for draining fluid at low pressure from the other side of the vane, said vane being operable at the completion of its stroke to open liquid supply means formed in the port plate to deliver liquid under pressure to one side of the second vane, said valve means providing for draining liquid at low pressure from the other side of said vane, said second vane being operable upon completion of its stroke to open by-pass means to relieve pressure from the high pressure side of said vane.

RUSSEL D. ACTON.

CERTIFICATE OF CORRECTION.

Patent No. 2,232,506.

February 18, 1941.

RUSSEL D. ACTON.

It is hereby certified that error appears in the printed specification of the above numbered patent requiring correction as follows: Page 4, second column, line 8, claim 8, for the word "having" read --being--; and that the said Letters Patent should be read with this correction therein that the same may conform to the record of the case in the Patent Office.

Signed and sealed this 1st day of April, A. D. 1941.

Henry Van Arsdale,
Acting Commissioner of Patents.
